UNITED STATES PATENT OFFICE

ANDRÉ COQUETTE, OF ESSONNES, FRANCE

BUTTON FASTENING

Application filed February 3, 1932. Serial No. 590,720.

The object of my invention is to provide means for the instantaneous fastening of buttons on articles of clothing or other articles, superseding to great advantage the usual 5 method of fastening buttons by sewing, which requires more time and fails to insure perfect solidity. The device according to my invention permits, moreover, removal of a button instantaneously without leaving any 10 trace on the fabric.

The device according to my invention comprises essentially a U shaped member, the two branches of which, traversing the button, are pointed at their extremities and provided 15 with an eyelet hole, said branches engaging in apertures provided in a fastening headpiece and secured by means of a sliding pin inserted through the eyelet holes.

Preferred embodiments of my invention 20 will be hereinafter described with reference to the accompanying drawing given merely by way of example and in which:

Fig. 1 is a side view, on a large scale, of 25 a button connected to the fastening headpiece;

Fig. 2 is a front view of the button alone;

Fig. 3 is a sectional view following line 30 III—III of Fig. 1;

Fig. 4 is a sectional view on line IV—IV of Fig. 3;

Fig. 5 is a perspective view of the U shaped 35 fastening member;

Fig. 6 is a perspective view of another embodiment of my invention.

In said drawing, 1 is the button itself and is represented as a disk provided with a rim. 2 is the removable fastening headpiece.

Disk 1 is provided, at its center, with a 40 projection 1a through which two apertures 1b have been drilled. Spurs 1c, intended to fasten into the cloth or other fabric in order to secure the button with added safety, may be provided, moreover, to great advantage, on 45 said projection 1a.

The two branches of a U shaped member 3, 50 the extremities 3a of which are pointed and provided with eyelet holes 3b, are inserted through said apertures 1b. Said extremities 3a engage in apertures 2a provided in headpiece 2, the depth of said apertures 2a being

such as to allow eyelet holes 3b to come exactly opposite an aperture 2b drilled through headpiece 2. A pin 4a, constituting one of the two branches of a U shaped member 4 the other branch 4b of which engages in a recess 2c provided in the headpiece, may slide in said aperture 2b. When said member 4 has been thoroughly driven into headpiece 2, as shown in Fig. 4, it projects slightly from said headpiece, forming a small loop. The extremity of branch 4b is bent back to form a hook 4c and a ring 5 is inserted in a groove 2d of headpiece 2, a catch 5a, which falls perpendicular to recess 2c, being formed on said ring 5.

The device according to my invention is operated as follows:

In Fig. 3, headpiece 2 is connected to button 1 and pin 4a is engaged through eyelet holes 3b of member 3. All that is necessary 55 in order to remove headpiece 2, is to draw out pin 4a by introducing, for instance, the point of a pin or of a needle into the loop formed by member 4 (Fig. 4). Member 4 is thus brought to the position indicated by 60 the line of dashes and held there, hook 4c butting against catch 5a. Headpiece 2 may 65 then be removed.

In order to fasten the button onto a piece 70 of cloth or any other article, the sharp ends 3a of member 3 are applied against said article, said member 3 being engaged in apertures 1b of said button. When said extremities 3a have been driven through the 75 fabric, they are engaged in apertures 2a of headpiece 2 and member 4 is driven back. Branch 4a is inserted through eyelet holes 3b, thus securing member 3 together with button 1 which it carries.

Fig. 6 shows another embodiment of the 80 fastening device according to my invention, the latter embodiment being particularly suitable to fasten buttons onto military uniforms, hunting suits or the like, without 85 modifying the construction of the device. Dot and dash lines indicate a button of this 90 sort provided, in the well known manner, with a small loop or ring 6a for fastening 95 purposes. U shaped member 3', which serves 100 to fasten said button and the extremities of

which are also provided with eyelet holes 3'b, is disposed crosswise with two prongs 7 intended to pierce through the fabric. The whole may easily be inserted through ring 5 6a of the button and combined with a fastening headpiece similar to that which has been described above.

- In order to allow the fastening member to be driven more easily through the fabric, 10 a tapered cylindrical rod 8 may be inserted through ring 6a of the button, behind said fastening member, so as to hold the latter in a suitable position for being driven through the fabric.
- 15 While I have disclosed what I deem to be preferred embodiments of my invention, I am not limited thereto, as there may be changes made in the construction, disposition and form of the parts without departing 20 from the principle of my invention as comprehended within the scope of the appended claims.

What I claim is:

1. A device for fastening buttons, comprising in combination, a U-shaped member secured to a button, both branches of said member having pointed extremities each provided with an eyelet hole, a fastening headpiece provided with two apertures in 25 which the branches of said U shaped member are engaged, and a sliding pin inserted in said headpiece and through the eyelet holes of said U shaped member so as to secure the latter to said headpiece.
- 30 2. A device for fastening buttons, comprising in combination, a U shaped member secured to said button, both branches of said member having pointed extremities each provided with an eyelet hole, a fastening 35 headpiece provided with two apertures in which the branches of said U shaped member are engaged, and a second U shaped member inserted in said headpiece, one of the branches of said second U shaped member passing through the eyelet holes of the first U shaped member.
- 40 3. A device for fastening buttons, comprising in combination, a U shaped member secured to said button, both branches of said member having pointed extremities each provided with an eyelet hole, a fastening 45 headpiece provided with two apertures in which the branches of said U shaped member are engaged, and a second U shaped member inserted into said headpiece, one of the branches of said second U shaped member passing throughout the eyelet holes of the first U shaped member and the curved part of said second U shaped member projecting 50 slightly from said headpiece when said member is in operative position.
4. A device for fastening buttons, comprising in combination with a button provided with apertures, a U shaped member, the 55 branches of said member engaging in said

apertures and having pointed extremities each provided with an eyelet hole, a fastening headpiece provided with two apertures in which the branches of said U shaped member engage, and a sliding pin inserted in said headpiece and through the eyelets of the U shaped member so as to secure the latter to said headpiece.

5. A device for fastening buttons, comprising in combination with a button provided with apertures, sharp projections on said button, a U shaped member, the branches of which engage in two of the apertures provided in said button and have pointed extremities each provided with an eyelet hole, a fastening headpiece provided with two apertures in which the branches of said U shaped member engage, and a sliding pin inserted in said headpiece and through the eyelets of the U shaped member so as to secure the latter to said headpiece.

6. A device for fastening buttons, comprising in combination with a button provided with a ring for fastening purposes, a U shaped member engaging in said ring, both branches of the former having pointed extremities provided with an eyelet hole, sharp prongs secured on said U shaped member, a fastening headpiece provided with two apertures in which the perforated branches of said U shaped piece engage, and a sliding pin inserted in said headpiece and through the eyelet holes of the U shaped member so as to secure the latter to said headpiece.

7. A button fastening comprising a U-shaped member insertable through openings in a button, a head in which the ends of said member are engaged and provided with a recess in one side, a U-shaped retainer having one side inserted in the head and through the ends of the U-shaped member, the other side of the retainer engaging in the recess in the head and provided with an outwardly projecting hook at its extremity, and a ring fitted about the head and having an internal hook cooperating with the hook on the retainer to prevent release of the retainer.

In testimony whereof I affix my signature.

ANDRÉ COQUETTE.
